(57) **CLAIM**

The ornamental design for an cat tunnel with bed, as shown and described.

DESCRIPTION

FIG. 1 is a front perspective view of a cat tunnel with bed, showing my new design in a use state;

FIG. 2 is rear perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of FIG. 1;

FIG. 9 is a partial enlarged view of FIG. 1; and,

FIG. 10 is a partial enlarged view of FIG. 2.

The dashed broken lines illustrate portions of the article that form no part of the claimed design, and the dash-dot-dash broken lines define the bounds of enlarged views in FIGS. 1, 2, 8, 9, and 10 and form no part of the claimed design.
